UNITED STATES PATENT OFFICE.

HARVEY D. TAYLOR, OF KEESEVILLE, NEW YORK.

PLIERS FOR APPLYING COUPLINGS OF WIRE.

SPECIFICATION forming part of Letters Patent No. 400,512, dated April 2, 1889.

Application filed December 3, 1888. Serial No. 292,555. (No model.)

To all whom it may concern:

Be it known that I, HARVEY D. TAYLOR, a citizen of the United States, residing at Keeseville, Essex county, New York, have invented 45
§ a new and useful Improvement in Pliers for Applying Couplings of Wire, of which the following is a specification.

My invention relates to improvements in pliers, such as are used in applying coupling-
10 bands of wire or metal to hose, pipe, or any-
thing held together by bands of wire or metal
drawn around it, which enable one to apply
the link of wire or metal as a band without
welding the ends of the wire or metal together,
15 as is now done with the pliers such as are now
in use. I attain this object by the device
illustrated in the annexed drawings, in
which—

Figure 1 is a side view of the pliers ready
20 for use. Fig. 2 is a side view of the upper
member of the pliers detached. Fig. 3 is a
side view of the lower part or member and its
spring detached. Fig. 4 is a side view of the
25 third part or lower jaw. Fig. 5 represents the
link of wire or other metal strip in the form
to be applied by my pliers. Fig. 6 represents
a link such as is now in use after being ap-
plied with pliers having two jaws or parts
30 only, the ends of which are caught into the
closed ends J L and tighten the link about
whatever it is to be applied to by closing the
handles of the pliers and thereby opening the
jaws of the pliers, thus drawing one end of
35 the link, as L, through the other, J, tightly.

Similar letters refer to similar parts in the
several figures.

In Fig. 4, *c d* represent the mortised or
halved portion of lower jaw, *O'*, which fits a
similar mortise or half, *c' d'*, of the lower mem-
ber, and the two are held together by a rivet
40 passing through a hole, *R*, in both. The part
B of the lower jaw, *O'*, is a tenon and made
to fit into a mortise, E, in the upper member
of the pliers, as shown by Fig. 2, and extends

to the dotted line *a*, and is held in place therein
by a rivet passing through both at *R'*. *S* is
a strong metal spring attached to the lower
member to throw the handles of the pliers
apart. *H* is a notch in the outer end of jaw
P of the upper member, in which the closed
end J of the link is caught in applying the
coupling of wire. *I I* are serrated faces upon
the jaws *O' O²*, to catch and hold the free ends
K K of the link or bent wire in applying it.

In use the link shown by Fig. 5 is passed
tightly around the thing to be coupled, bound,
or joined, and the ends K K are passed under
the closed end J. The jaws *I I* of the pliers
are then applied to the open or free ends K K
(grasping them) of the link or wire, and the
notch *H* is caught under the closed end J of
the link. The arms of the pliers *m n* are
then pressed together, which causes the jaws
O' O² to clasp firmly with their serrated faces
I I the open or free ends K K of the link,
while at the same time the lever or jaw P, hold-
ing the closed end of the link in its notch *H*,
moves in a direction opposite to that of the
jaws *O' O²*, and thus draws the ends K K of
the link through the closed end J tightly, and
then by simply bending or turning the pliers
over the closed end of the link the fastening
is made.

What I claim as my invention, and wish to
secure by Letters Patent, is—

The pliers described, consisting of two main
members or arms and a short connecting mem-
ber, the upper member, *m*, having the exten-
sion *P*, and provided with a notch, *H*, the
lower member, *n*, having an upper jaw, *O²*,
the connecting member having the jaw *O'*
and being pivoted to the lower member and
also to the head of the upper member, as set
forth.

HARVEY D. TAYLOR.
